CLAIM

The ornamental design for a telephone stand for a handset transceiver, substantially as shown and described.

DESCRIPTION

FIG. 1 is a top and right side perspective view of a telephone stand for a handset transceiver showing our new design;

FIGS. 2 and 3 are respectively right and left side elevational views thereof;

FIG. 4 is a bottom plan view thereof;

FIG. 5 is a rear elevational view thereof;

FIG. 6 is a top plan view thereof; and

FIG. 7 is a front elevational view thereof.

FIG. 1

FIG. 2

FIG. 3

FIG. 4

FIG. 5

FIG. 6

FIG. 7
